EDWARD PIERSON AND SIMON L. DUNLAP, OF INDIANAPOLIS, INDIANA;
SAID PIERSON ASSIGNOR OF FOUR-TENTHS OF HIS RIGHT TO SAID
DUNLAP.

REMOVABLE CALK FOR HORSESHOES.

No. 828,422.

Specification of Letters Patent.

Patented Aug. 14, 1906.

Application filed March 19, 1906. Serial No. 306,842.

To all whom it may concern:

Be it known that we, EDWARD PIERSON and SIMON L. DUNLAP, citizens of the United States, residing at Indianapolis, in the county 5 of Marion and State of Indiana, have invented certain new and useful Improvements in Removable Calks for Horseshoes, of which the following is a specification.

This invention relates to an improvement 10 in horseshoe-calks; and the object of the invention is to provide calks that can be easily placed into or removed from the shoe when the latter is attached to the horse's hoof.

The object consists, further, in providing a 15 calk for horseshoes which is so arranged that when it has become worn to a certain point the clamping means will drop out, and thus permit the calk to lose itself from the shoe. This last feature is one of the main objects of 20 this invention, for the reason that it is more desirable to have a worn calk entirely removed from the shoe than to be continued in service and to interfere with the movement of the horse.

25 The accompanying drawings illustrate the invention, in which—

Figure 1 is a perspective view of a horseshoe, showing our improved calks in operating position. Fig. 2 is a longitudinal vertical 30 sectional view of a calk, showing the manner in which the members comprising said calk are secured together. Fig. 3 is a top or plan view of a calk with the shoe omitted. Fig. 4 is a perspective view of a calk having its sides 35 sloped to an edge to insure a more perfect footing for a horse on slippery pavements during the winter.

In the drawings, 1 represents the body of the horseshoe, which is provided with three 40 elongated downward and inward sloping slots, which receive the upper ends of the calks. The body of the calk comprises the two members 4 and 5, which are set together, and the intervening joining-line is cut on a 45 diagonal plane, as shown. The upper ends of said members are cut on diagonal lines that taper toward each other, and thus form a lock or key for the calk when the members 50 4 and 5 are nested together in operating position. The elongated slots in the shoe-body 1 are formed with tapering ends that correspond with the upper key ends of the members 4 and 5. In placing the calk into operating 55 position the member 4 is first inserted into

the elongated slot in the shoe-body, and after 55 said member is seated the member 5 may readily be placed into position. The members 4 and 5 of the calk are provided with a longitudinal aperture 8, which registers when said members are in operating position, and a 60 split key 9 is passed through said aperture, and by spreading the ends of the key the two members are tightly drawn together. All 65 possibility of the calk being accidentally disengaged from the shoe 1 is now prevented.

The horseshoe-calks in general use seriously interfere with the movement of the animal when they have become irregular through wear, and an irregular-worn calk is considered more harmful than no calk at all. We 70 have combined in this calk a feature which will permit the calk to free or lose itself from the shoe when the metal has worn down to the longitudinal aperture 8, thus permitting the split key 9 to drop out. With the use of 75 this invention the life of the horseshoe is greatly prolonged and the condition of the horse's hoofs preserved, for the reason that the shoes are removed only when it becomes necessary to re-dress the animal's hoofs. 80 The driver usually carries a number of the calks, so that when one becomes badly worn another can readily be substituted. In order to prevent any lateral movement between the members 4 and 5, we slightly channel the 85 abutting end of the member 4, while the adjacent end of the member 5 is made to fit said channel. (See Fig. 3.)

Fig. 5 is a perspective view of a calk the sides of which taper to a point, making it 90 more desirable and efficient during the winter months, when ice and sleet are usually encountered. Otherwise the calk is made similar to the one disclosed in Figs. 2 and 3, which has previously been described.

Having thus fully described our said invention, what we desire to secure by Letters Patent of the United States is—

1. In a removable calk for horseshoes comprising a shoe provided with slots the sides of 100 which slant downwardly and inwardly toward each other, a calk formed of a plurality of members and having its upper portion to register with the slot in the shoe, and locking means for securing the calk-forming members together.

2. In a removable calk for horseshoes comprising a shoe provided with slots the sides of 105

- which slant downwardly and inwardly toward each other, a calk formed of a plurality of members and having its upper portion formed on downwardly and inwardly extending inclined planes to register and engage with the slot in the shoe, and having their abutting ends cut diagonally of the perpendicular, and locking means passing through the calk members to secure them together.
- 10 3. In a removable calk for horseshoes comprising a shoe provided with slots the sides of which slant downwardly and inwardly toward each other, a calk formed of a plurality of members and having its upper portion formed on downwardly and inwardly inclined
- 15

planes to register and engage with the slot in the shoe, the abutting end of one of the members being channeled and the adjacent end of the other member formed to fit said channeled end, and locking means for securing the 20 calk-forming members together.

In witness whereof we have hereunto set our hands and seals, at Indianapolis, Indiana, this 29th day of February, A. D. 1906.

EDWARD PIERSON. [L. s.]
SIMON L. DUNLAP. [L. s.]
